UNITED STATES PATENT OFFICE.

CASPER A. KENNE, OF WHITTEMORE, IOWA.

SUPPORTING ATTACHMENT FOR VIOLINS.

Application filed October 3, 1921. Serial No. 504,964.

To all whom it may concern:

Be it known that I, CASPER A. KENNE, a citizen of the United States, residing at Whittemore, in the county of Kossuth and 5 State of Iowa, have invented certain new and useful Improvements in a Supporting Attachment for Violins, of which the following is a specification.

This invention relates to improvements in 10 supporting attachments for violins, and it consists in certain peculiarities of the construction, novel arrangement and combination of the various parts thereof as will be hereinafter more fully set forth and specifically claimed.

The object of the invention is to furnish 15 a very simple and inexpensive device to be used in connection with a violin, for supporting the same on the body of the user or performer, in such a way as to perfectly position the instrument and to avoid the tendency of the violin to slip downward on the chest of the user, as well as to prevent the instrument from tipping forwardly, or 20 twisting.

Another object is to provide an attachment of the above mentioned general character, which can be readily attached to or removed from a violin and its parts easily, 25 detached one from another for the purpose of facilitating their carriage in a violin case.

Other objects and advantages of the invention will be disclosed in the following description and explanation.

30 In the accompanying drawings, which serve to illustrate an embodiment of the invention—

Fig. 1 is a bottom plan view of a violin with my attachment mounted thereon with 35 its parts in about the positions they will occupy when ready for use.

Fig. 2 is an inverted view in side elevation of the parts shown in Fig. 1.

Fig. 3 is a rear end view of the violin 40 showing it inverted and illustrating the attachment as being held in place by the clip of a chin rest on the violin body.

Fig. 4 is a fragmental perspective view 45 of a portion of the body of a man showing about the positions the parts of my improved attachment will occupy with respect to his body when the violin is supported by such attachment. In this view the body of the violin, as well as that of the man, is 50 shown in dotted lines.

Fig. 5 is a detached grouped view of the

parts of the attachment looking at them from their lower surfaces, and

Fig. 6 is a cross-sectional view taken on lines 6—6 of Fig. 5 showing the construction 60 of the socketed members of the attachment.

Like numerals of reference refer to corresponding parts throughout the different views of the drawings.

The reference numeral 10 designates the 65 body of a violin on the rear end and upper surface of which is mounted a chin rest 11, which chin rest may be of the ordinary or any preferred construction, but by preference has extended therefrom a pair of connections 12 which engage a flange or hook 13 located on the lower surface of the rear end of the violin and in engagement with the rim thereof. The connections 12 may be adjustably connected to the chin rest 11 70 and flange 13 by the parts 12 which co-act with the chin rest and flange in the manner of turn-buckles to draw said parts towards each other in order to firmly hold the chin rest in position on the violin.

As shown in Figs. 1 and 2, as well as Fig. 3, the flange or hook 13 of the clip of the chin rest ordinarily lies in close contact with the bottom of the violin, but when the chin rest clip is employed in connection 85 with my attachment, a supporting member, designated as a whole by the numeral 14 and having a deflected tongue 15 at one of its ends, is interposed between the flange 13 and the adjacent surface of the violin, that 90 is, the end of the deflected tongue 15 of the supporting member 14 is so positioned. This supporting member is by preference made of sheet metal and has flanges 16 at its side edges folded inwardly or towards each other to provide a socket 17 for the member to 95 be engaged thereby as will be presently explained.

While I have shown the socket member 14 as being held on the violin body by means 100 of a chin rest clip, yet I wish it to be understood that I do not desire to be limited to such means for mounting the socket member on the violin as it can be secured thereto at the proper point on the lower surface 105 of the violin body by any suitable means, but of course it will be understood that the chin rest clip affords a convenient means for this purpose.

Fitted in the socket 17 of the member 14 is 110 a tongue 18 extended diagonally above and across an arm 19 which is provided at its

end opposite the tongue 18 with a transversely disposed extension 20 which is upwardly bowed and provided on its lower surface with a pad 21 of any suitable material 5 to rest against the chest or breast of the violinist.

As is clearly shown in Fig. 5 of the drawings, the arm 19, tongue 18 thereof, and extension 20, are preferably made of a single 10 piece of material, and the arm 19 has a bend as at 22 towards the body of the user, in order to cause the pad 21 and extension 20 therefor to rest slightly diagonally on the breast of the user.

15 That end of the arm 19 opposite the extension 20 is adapted to be inserted in a socket member 23 with which the inner end of an arcuate shoulder rest 24 is provided. This shoulder rest is curved as shown in the 20 various views of the drawings to correspond with the contour of the shoulder of the user of the instrument, and when slid on the free end of the arm 19, will be held in place by means of a pin 25 on said arm engaging a suitable recess 26 in the socket member 23.

From the foregoing, and by reference to the drawings, it will be clearly seen and readily understood that I have provided by 30 my improvements a support for violins which, when attached to the rear lower portion of the body of a violin, will provide means for a shoulder rest to prevent the violin slipping down on the body of the user, 35 and it is also manifest that a breast-rest will be furnished to prevent tipping of the violin body as well as twisting thereof. The shoulder-rest 24 extends slightly over the shoulder and rearwardly thereof, and as it 40 is curved to conform to the curvature of the shoulder, it is manifest that the violin will be securely held in the proper position and with comfort to the user.

While I have shown one embodiment of

the invention, yet I do not wish to be limited 45 to the exact construction thereof as herein above described and shown in the drawings, for it is apparent that various slight changes in the construction of the device may be made without departing from the spirit of 50 the invention.

Having thus fully described my invention, what I claim as new and desire to secure by Letters Patent is:—

1. A supporting attachment for violins 55 comprising a supporting member secured to the lower surface of the rear end of a violin and extended in the direction of the front end thereof, a breast-rest having an arm extended from one of its edges near one of its 60 ends, said arm being extended diagonally across and below said supporting member, a shoulder rest detachably mounted on the rear portion of said arm and extended rearwardly beyond the rear end of the violin to 65 rest on and over the shoulder of the user thereof, a tongue extended from the breast-rest-arm diagonally across the same and detachably mounted on the said supporting member. 70

2. A supporting attachment for violins comprising a socketed supporting member secured to the lower surface of the rear end of a violin and extended in the direction of the front end thereof, a breast-rest having 75 an arm extended from one of its ends, said arm being extended diagonally across and below said supporting member, a shoulder-rest detachably mounted on the rear portion of said arm and extended rearwardly 80 beyond the rear end of the violin to rest on and over the shoulder of the user thereof, a tongue extended from the breast-rest arm diagonally across the same and detachably mounted on said socketed supporting member. 85

CASPER A. KENNE.
